This invention relates to a receptacle device for receiving and holding refuse such as fragments of paper, rags, and the like which are to be disposed of by burning. The device is intended to be a reliable receptacle for holding refuse until it is ready to be disposed of by burning. It is designed to be simple in construction and easy to use. It is also designed to be durable and to withstand the effects of the elements without material injury or impairment. It is also designed to be economical of manufacture, and neat in appearance; and that it will lend itself to economy and facility in transportation, distribution, and merchandising.

UNITED STATES PATENT OFFICE

RECEPTACLE

Earl F. Smith and Guy Kenneth Wilson, Muncie,
Ind.

Application December 13, 1938, Serial No. 245,470

2 Claims. (Cl. 220—30)

This invention relates to improvements in articles made of wire, reference being had especially to a device of this class which is intended for the receiving and holding of refuse such as fragmentary quantities of paper, rags, and the like which are to be disposed of as by burning.

In a device of the above description and which is referred to as a receptacle, it is desirable that the closure thereof shall be dependable, easy to manipulate, not liable to get out of order or repair, and that it will withstand the effects of the elements without material injury or impairment. Also that it may be economical of manufacture, and neat in appearance; and that it will lend itself to economy and facility in transportation, distribution, and merchandising.

To provide a receptacle affording the above named advantages as well as other benefits which will be apparent as the specification of our invention proceeds, is the object of our invention. The invention is embodied in the new construction, combination and arrangement of parts illustrated in the accompanying drawing and described in the following specification. The several parts of the invention are identified by suitable characters of reference applied to them in the different views in the drawing, in which—

Figure 1 is a side view of our improved receptacle, the closure members being in the reclined or open position.

Figure 2 is an enlarged top plan view of Figure 1, in the direction of arrow 2 in Figure 1.

Figure 3 is a fragmentary enlarged view of the lug detail of the receptacle and the terminal portions of the closure bows which are articulated therewith, as they appear in the status indicated in Figure 1.

Figure 4 is a side view of the top portion of the receptacle showing the relative positions of the several parts when the closure members are in the expanded or covering position.

Figure 5 is a view taken in the direction of arrow 5 in Figure 4.

Figure 6 is an enlarged view of the lug detail of the receptacle, and the terminal portions of the closure members which are articulated therewith, as they appear in the expanded position indicated in Figure 4.

The receptacle may be of the typical formation and construction as illustrated in the drawing. Upright wires 1, 1, spaced as shown, have their lower ends secured to a base ring 2, and at their upper ends they are secured to the substantial top ring and which hereinafter, is designated 55 as the rim of the receptacle.

Intermediate rings 7, 8 and 9, and to which the aforesaid upright wires are secured, stay the latter in their spaced relation. A grating consists of wires 10, 10 and 12, 12 arranged and interconnected in spaced criss cross relation, and which said wires are integrated at their ends with ring 14. A seat for the said grating consists of an internal ring 16 which is supported by the upright wires at such height as may be desired.

At each of the diametrically opposite side portions 3 and 4 of the said rim, is secured a lug which embodies two arches and which are interrelated, one being designated as the main arch 17, and the other, and which is of lesser height, being designated as the secondary arch 18. These arches are so interrelated, that the leg of the secondary arch is at position between the vertical axis and a leg of the main arch. In structure, the said arches so embodied in this lug as above described, may consist of wires substantially as shown in the drawing, and which are integrated at their bottoms to the rim of the receptacle, as by welding. Each of the said lugs is so positioned that the axis L—L of the main arch is slightly offset from the axis R—R of the receptacle, the reason for which will presently be referred to.

Each of similar cross members, which we designate as bows, consists of a length of wire of semi-circular bend, each terminal portion thereof being looped as by an eye 21 into loose engagement with the arch 17. Slender chains 22 each of predetermined length and which interconnect the said bows, and a similar chain 23 which interconnects the lowermost bow 24 and the median portion 5 of the receptacle rim, constitute collapsible linkage which permits of the bows being reposed one upon the other, as shown in Figure 1 and in Figure 3, and of their being moved to spaced positions as shown in Figure 4. One of the outer bows, namely bow 24 is designated as the lowermost bow; and the other of the outer bows, namely the bow 32 is designated as the uppermost bow. Loose on the uppermost bow is a connector member which preferably consists of a light chain 33 at whose free end is embodied a hook 34. This connector member 33 is of such length that when it is drawn toward, and its hook will have been engaged with the confronting median portion 6 of the receptacle rim, the said connector member 33 and the interconnecting members 22 and 23 are taut, as shown in Figure 4. It will be observed, in reading the drawing at Figure 4, that the terminal portion of the uppermost bow 32 rests upon the arch 18, and that its
